DIRECT READOUT TEST AND MEASUREMENT INSTRUMENT

William A. Lang, Clayton, Mo., assignor to Monsanto
Company, St. Louis, Mo., a corporation of Delaware

Continuation of design applications Ser. No. 85,534 and
Ser. No. 85,536, June 1, 1965. This application July 29,
1966, Ser. No. 4,074

Term of patent 14 years

(Cl. D26—1)

FIG. 1

FIG. 2

FIG. 3

FIG. 4

FIG. 1 is a perspective view of a direct readout test and measurement instrument showing the front, top and left side of my new design;

FIG. 2 is a perspective view showing the rear, bottom, and right side of the instrument design of FIG. 1;

FIG. 3 is a perspective view of the direct readout test and measurement instrument of FIG. 1 showing a modified embodiment thereof wherein push buttons are employed in lieu of radial knobs; and

FIG. 4 is a perspective view showing the rear, bottom and right side of the design of FIG. 3.

The essential features of my design are shown in full lines, being characterized by the combination of a front panel divided along a center vertical line and having the controls grouped to the right of said line and the information readout to the left thereof behind a transparent panel which covers the entire left half of the front panel, and the particular rectangular vertical hand grips disposed at either end of said front panel, all as shown.

This application is a continuation of my applications Ser. No. D-85,534, filed June 1, 1965, and Ser. No. D-85,536 also filed June 1, 1965, both now to be abandoned.

I claim:

The ornamental design for a direct readout test and measurement instrument, as shown and described.
